UNITED STATES PATENT OFFICE.

GEORGE ALBERT SPRATT, ALFRED SIDNEY SPRATT, AND HENRY JAMES SPRATT, OF LONDON, ENGLAND.

MACHINE FOR MAKING HAIR-PINS.

SPECIFICATION forming part of Letters Patent No. 350,900, dated October 12, 1886.

Application filed May 29, 1886. Serial No. 203,673. (No model.)

To all whom it may concern:

Be it known that we, GEORGE ALBERT SPRATT, ALFRED SIDNEY SPRATT, and HENRY JAMES SPRATT, cabinet-makers, subjects 5 of the Queen of Great Britain, and all residents of London, England, have invented new and useful Improvements in Machinery or Apparatus for Making Hair-Pins, of which the following is a specification, reference being 10 had to the accompanying drawings.

The machinery or apparatus which we employ in the manufacture of our hair-pins comprises means for feeding the wire as required from a reel or drum on which it is wound, 15 means for gripping or holding the end of the wire to permit the coiling thereof on the mandrel, means for cutting the same into blanks or pieces of suitable length and pointing the same by one operation, means for rotating the 20 mandrel and imparting longitudinal motion thereto to spirally wind or coil the said pieces thereon, and means for withdrawing the said mandrel from the hair-pins thus formed.

In the accompanying drawings, Figure 1 is 25 a plan, partly in horizontal section, of our improved machine or apparatus. Fig. 2 is a section on the line $x-x$, Fig. 1, some of the parts being removed. Fig. 3 is an elevation, partly 30 in section, on the line $x'-x'$, Fig. 1, some of the parts being removed. Fig. 4 is an end elevation of part of the said machine. Fig. 5 is a side elevation of a hair-pin made by the said machine.

a is the bed-plate of the machine.

35 b is a hollow shaft, which is carried in suitable bearings in the uprights or standards a' a'' . c is a driving-pulley fitted to rotate upon the said shaft. d' is a pinion, which is secured to the said pulley and gears with a toothed 40 wheel, d' , fixed on a shaft, d , carried in bearings in the uprights or standards a' a'' .

e is the mandrel, which is fitted to slide longitudinally to and fro within the shaft b , and is so connected with the said shaft that it will 45 rotate therewith. For instance, the mandrel is made with a square portion fitting into a square hole in the said shaft. The mandrel extends through the said shaft, and is acted upon by a spring, f , which tends to keep it in 50 the position shown. This spring is attached at one end to the bed-plate a , and at its other

end to a forked piece, f' , whereby it is connected with a spindle, g , fitting into a socket, e' , formed or fixed on the end of the mandrel. The spindle g carries an anti-friction roller, g' , 55 and is secured in the socket e' by means of a screw, g'' , which is screwed into the said socket and enters an annular groove or channel in the spindle g . The mandrel, therefore, although connected with the spindle g , is capable of 60 rotation independently thereof. The rotation of the said spindle is prevented by the spring f . A pinion, d , is fixed on the shaft d , and gears with a toothed wheel, h , fixed on the shaft h , which is carried in bearings in the 65 uprights or standards a' a'' . A cam, i , is fixed upon the shaft h , and is formed with a helical surface, i' . In each revolution of the shaft h this cam moves the mandrel e in one direction against the pressure of the spring f , (the roller g' running on the helical surface i'), and then permits the said spring to effect the return movement of the said mandrel—that is to say, to move it back to its original position. The mandrel is thus moved to and fro once in each 75 revolution of the shaft h , for the purpose hereinafter specified.

k is a reel containing the wire from which the hair-pins are to be made. This reel is fitted to rotate on a pin or bolt, k' , carried by brackets k'' , attached to the bed-plate a . This pin is so arranged that it can easily be withdrawn when it is desired to remove an empty reel and substitute a fresh reel therefor. The wire from this reel is passed through a tubular 85 shaft, l , secured in the upright or standard a' . A sleeve, m , is fitted upon the shaft l and bears against a conical seat, l' , thereon. This sleeve is secured upon the said shaft by means of a nut, n , having a conical extension, n' , which fits a corresponding seat in the sleeve m ; but the said sleeve is free to rotate upon the said shaft. A driving-pulley, 90 m' , is fitted with a capability of to-and-fro movement upon the sleeve m , but is keyed 95 thereto, or otherwise connected therewith, so that the said sleeve will rotate with the said pulley. This pulley is to be connected by a belt with a pulley on an overhead shaft. Two levers, o o' , are pivoted at o' o' to lugs formed 100 on the sleeve m . Each of these levers has a circular cutter, o'' , fitted to rotate upon one arm

thereof. The other arms of the said levers extend toward the pulley m' , in which are fixed the brackets or studs m^2 , provided with anti-friction rollers m^3 . These rollers bear against 5 the levers o , as shown. The sleeve m , levers o , and cutters o^2 all rotate upon or about the shaft l with the pulley m' . A ring or collar, r , is fitted to slide to and fro upon the shaft l , between the pulley m' and the upright or 10 standard a^5 . Two pins or rods, r^3 , are fixed in this ring or collar, and extend through holes in the upright or standard a^5 . A flanged sleeve, p , is fitted to slide to and fro upon a rod or shaft, p' , carried in the uprights or standards 15 $a^5 a^6$, below the shaft l . This sleeve is coupled by means of a connecting-rod, p^2 , with a crank, q , formed on or attached to the bevel-pinion q' . The said crank and bevel-pinion are fitted to rotate upon a stud or shaft, q^2 , firmly secured to the bed-plate a . The connecting-rod 20 p^2 is made in two parts, which are united by bolts passing through slots therein, so that the said rod can be lengthened or shortened, as required, to regulate the position of the 25 sleeve p relatively to the pins or rods r^3 . This sleeve is provided with a spring-catch, p^3 , for holding the wire when the said sleeve is moved forward to feed the said wire to the mandrel e . One of the pins or rods r^3 is made with an 30 extension, r^4 , which passes through the flange of the sleeve p , so that at the moment when the said pins are acted upon by the said sleeve the extension r^4 will disengage the catch p^3 from the wire, and thus prevent any forward 35 movement of the wire while the same is being cut. A similar catch, p^4 , is provided on the upright or standard a^6 , to prevent backward movement of the said wire. A spring, m^4 , is placed upon the sleeve m , to effect the return 40 movement of the pulley m' , and to permit the cutters o^2 to be moved back to their normal position, which movement is effected either by centrifugal force or by means of a spring or springs suitably arranged in combination with 45 the levers o . Motion is imparted to the crank q by means of a bevel-pinion, r , fixed on the shaft h and gearing with the pinion q' . A tube, s , is carried by a bracket, s' , secured to the bed-plate a . This tube is so placed that it 50 will conduct the wire from the tubular shaft l to the mandrel e .

t is a rod or spindle, which is fitted to slide to and fro in a hollow shaft, t' , and is so connected with the said shaft that it will rotate therewith. The shaft t' is carried in bearings 55 in the uprights or standards $a^7 a^8$. The said rod or spindle is acted upon by a spring, u , which is attached to the bed-plate a , and bears against one end of the said rod or spindle, so 60 that it tends to force the same into contact with the mandrel, the said rod or spindle and the mandrel being in axial alignment. Rotary motion is imparted to the hollow shaft t' , and consequently to the rod or spindle t , from the 65 shaft b , through the medium of the shaft v , carried in bearings in the uprights or standards

a' a^8 , and having fixed thereon the pinion v' , gearing with the pinion b^2 on the shaft b , and the pinion v^2 , gearing with a pinion, r^2 , fixed upon the hollow shaft t' . These pinions are 70 so proportioned that the rod t will be rotated at the same velocity as the mandrel e .

w is a catch-lever, which is pivoted at w' upon a stud, w^2 , fixed in the bed-plate a . This lever is so shaped at one end that it will enter 75 an annular groove or recess, t^3 , in the rod t , and is acted upon by a spring, w^3 , which tends to hold the said lever in engagement with the said rod.

The gearing whereby the driving-pulley c 80 is connected with the shaft h and crank q is so arranged that while the said driving-pulley is making, say, twelve or sixteen, or any other desired number of revolutions, the shaft h and crank q will make only one revolution. Moreover, the cam i is so shaped that during one half of each revolution thereof it will move the mandrel forward or toward the rod t , and during the other half of each revolution will permit the movement of the said mandrel in the reverse 85 direction by the spring f .

To provide for automatically putting the shaft b and mandrel e in and out of gear with the driving-pulley c , a pin or stud, b^3 , is fixed in the pinion b' , and a sleeve or clutch, y , is 90 fitted to slide to and fro upon the shaft b , and is provided with a pin or stud, y^3 . This sleeve or clutch is keyed upon the shaft b , so that the said shaft will rotate therewith. A ring, y^2 , is fitted upon the sleeve or clutch y in such a 95 manner that the said sleeve or clutch is free to rotate therein. A forked lever, z , is pivoted upon a pin or stud, z' , fixed in the bed-plate a . The forked end of this lever is connected with the ring y^2 by means of the pins or bolts 100 y^3 . The said lever is provided with a bracket or lug, z^2 , which carries an anti-friction roller, z^3 . The said lever is acted upon by a spring, z^4 , which tends to keep the roller z^3 against a cam, h^2 , fixed upon the shaft h . This spring 105 is attached at one end to the lever z , and at its other end to a pin or stud, z^5 , fixed in the bed-plate a .

In the operation of the machine the shaft h 110 is continuously rotated through the medium of the pinions b' d^2 and toothed wheels $d' h'$. In the rotation of the shaft h the cam h^2 , acting upon the lever z , moves the sleeve or clutch y toward the pinion b' , so that the stud y^3 engages with the stud b^3 , thereby putting the 115 shaft b in gear with the driving-pulley c . The said shaft is thus kept in gear while the shaft h is making one-half of a revolution, and while the cam i is moving the mandrel forward. The cam h^2 then releases the lever z at the same time 120 that the mandrel is drawn backward by its spring f , so that the said lever z is drawn by its spring z^4 back to its original position, thereby disconnecting the shaft b from the driving-pulley. The shaft b is therefore stationary 125 while the wire is being fed toward the mandrel.

The operation of the said machine is as fol-

lows, that is to say: The wire from the reel *k* is conducted through the catches *p*³ *p*⁴ and through the shaft *l* and tube *s*. The parts of the machine are shown in the drawings in the 5 positions which they occupy when the wire has been fed forward until its end is in proximity to the mandrel *e*. Assuming the machine to be started from this position, when the crank *q*, which moves in the direction indicated by the arrow in Fig. 1, reaches its forward "dead-center," the end of the wire lies between the end of the mandrel *e* and the rod *t*. The said rod is released by the striking of the crank *q* against the lever *w*. It is then 10 moved toward the mandrel *e* by the spring *u*, so that the end of the wire is firmly held between the mandrel and the rod *t*, the extremity of which is grooved or recessed to receive the end of the wire. Moreover, the crank *q* acts, through the medium of the connecting- 15 rod *p*² and sleeve *p*, upon the pins *t*, thereby forcing the rollers *n*³ between the levers *o* and bringing together the cutters *o*², so that they sever a piece from the wire and point the 20 said piece, the catch *p*³ being simultaneously disengaged from the wire by the extension *t*⁴. The cam *h*² then acts upon the lever *z* and puts the shaft *b* in gear with the driving pulley, so that the mandrel *e* is rotated. The 25 said mandrel is at the same time moved forward by the cam *i*. It therefore winds or coils the said piece of wire spirally upon itself. The cam *i* then permits the spring *f* to effect the return movement of the mandrel, 30 and the cam *h*² at the same time permits the spring *z*⁴ to throw the mandrel out of gear. In the return movement of the mandrel the hair-pin formed thereon is pushed off the same by the end of the tube *s*, or by the bracket sup- 35 porting the same. The rod *t*, which has been pushed by the mandrel back to its original position, as shown, remains in this position by reason of the engagement of the lever *u* therewith. The crank *q* in its return move- 40 ment moves back the sleeve *p* upon the rod *p*², and causes the catch *p*³ to engage with another length of wire preparatory to feeding forward the same. The upright or standard *a*⁵ is secured to the bed-plate *a* by means of bolts *a*⁶, 45 passing through slots *a*¹⁰ in the said bed-plate, so that the feed mechanism can be readily adjusted to and secured in any desired position relatively to the mandrel. Moreover, the sleeve *p* is adjustable on the rod or spindle *p*² by lengthening or shortening the connecting- 50 rod *p*², and the throw of the crank *q* can be increased or diminished by adjusting the crank-pin in the slot *q*⁶ in the said crank. The length of the pieces cut from the wire can therefore 55 be regulated with great facility.

The construction of our improved machine may be considerably varied without departing from the nature of our invention.

What we claim is—

60 1. In a machine for the manufacture of hair-pins, the combination of means for cutting and

pointing the wire to form blanks or pieces of suitable length, a mandrel, and means for spirally winding or coiling said blanks or pieces upon said mandrel, substantially as and for 70 the purpose set forth.

2. In a machine for the manufacture of hair-pins, the combination of means for intermittently feeding the wire from a reel or drum, means for cutting and pointing said wire to 75 form blanks or pieces of suitable length, a mandrel, and means for spirally winding or coiling said blanks or pieces upon said mandrel, substantially as and for the purpose set forth.

3. In a machine for the manufacture of hair-pins, the combination, with the mandrel *e*, of the hollow shaft *b*, the driving pulley *c*, the shaft *h*, connected by toothed gearing with said pulley, the cams *h*² *i*, fixed on said shaft *h*, the clutch *y* and its operating-lever *z*, and the 80 springs *f* *z*⁴, all substantially as and for the purposes set forth.

4. In a machine for the manufacture of hair-pins, the combination, with the mandrel *e* and means for operating the same, and the reel or 85 drum *k*, of the sliding sleeve *p*, provided with the catch *p*³, and the crank *q*, connected with said sleeve and operated by the shaft *h* through the medium of bevel-pinions, all substantially as and for the purposes set forth. 95

5. In a machine for the manufacture of hair-pins, the combination, with the mandrel *e* and means for operating the same, the reel *k*, and the sliding sleeve *p* and means for imparting reciprocating motion thereto, of the tubular 100 shaft *l*, sleeve *m*, pulley *m*¹, carrying rollers *m*³, levers *o*, cutters *o*², and ring or collar *t*², provided with pins or rods *t*, one of which has an extension, *t*⁴, all substantially as and for the purposes set forth. 105

6. In a machine for the manufacture of hair-pins, the combination, with the mandrel *e* and means for operating the same, the reel *k*, means for intermittently feeding the wire therefrom to said mandrel, and means for cutting and pointing said wire, of the tube *s* and bracket or support *s*, substantially as and for the purposes set forth. 110

7. In a machine for the manufacture of hair-pins, the combination, with the mandrel *e* and 115 means for operating the same, the reel *k*, means for intermittently feeding the wire therefrom to said mandrel, and means for cutting and pointing said wire, of the rod or spindle *t*, fitted to slide in the hollow shaft *t*¹, and operated 120 through the medium of the shaft *b*, pinions *b*² *v*¹, shaft *v*, and pinions *v*² *t*², and means for holding said rod or spindle out of contact with said mandrel until the wire has been fed or moved forward, and for automatically releasing it and 125 pressing it into contact with said mandrel to grip the end of said wire, all substantially as and for the purposes set forth.

8. In a machine for the manufacture of hair-pins, the combination, with the mandrel *e* and 130 means for operating the same, the reel *k*, means operated by the crank *q* for intermittently

feeding the wire from said reel to said mandrel, and means for cutting and pointing said wire, of the rod or spindle *t*, fitted to slide to and fro in the hollow shaft *t*, means for imparting motion from the shaft *b* to said rod or spindle, the spring *u*, and the lever *w*, acted upon by the spring *w*, and adapted to engage with said rod or spindle and to be released therefrom by said crank, all substantially as set forth.

In testimony whereof we have hereunto signed our names in the presence of two subscribing witnesses.
